UNITED STATES PATENT OFFICE.

ROBERT B. COCHRANE, OF CHARLOTTE, NORTH CAROLINA, ASSIGNOR, BY DIRECT AND MESNE ASSIGNMENTS, TO PERFECT BOTTLE OPENER COMPANY, OF CHARLOTTE, NORTH CAROLINA, A CORPORATION OF NORTH CAROLINA.

BOTTLE-OPENER.

1,247,507.

Specification of Letters Patent. Patented Nov. 20, 1917.

Application filed October 13, 1915. Serial No. 55,686.

To all whom it may concern:

Be it known that I, ROBERT B. COCHRANE, a citizen of the United States, residing at Charlotte, in the county of Mecklenburg and 5 State of North Carolina, have invented new and useful Improvements in Bottle-Openers, of which the following is a specification.

The present invention relates to bottle openers and is more concerned with devices 10 of this class for removing crimped caps from the mouths or heads of bottles, jars or the like.

The purpose of the invention is to improve the construction of devices of the 15 above-mentioned character by simplifying their construction and producing such a device that will operate with great efficiency without subjecting the bottle to the liability of breaking during the operation of the 20 machine.

The features of the invention reside in the novel construction, arrangement and combination of parts which will appear and be 25 readily understood as the specification proceeds; and, in the provision of means co-operative with the cap removing means and actuated thereby for ejecting the removed caps or stoppers from the machine.

In the drawings which form part of the 30 specification—

Figure 1 is a side sectional elevation taken through the housing of the machine and illustrating the bottle clamping means in 35 section for the sake of appearance; and

Fig. 2 is a horizontal sectional view taken substantially on line 2—2 of Fig. 1 with the clamp retaining plate removed.

Similar characters of reference designate 40 corresponding parts throughout the specification and drawings.

The invention, as shown in the drawings, consists of a frame A having a base portion 1 and a goose-neck extension 2 carrying and supporting the plunger 3 which is adapted 45 to act upon the bottle cap C of the bottle B suitably supported or clamped on the base 1 of the machine.

This device is especially designed to remove the caps or stoppers of bottles which

have said caps crimped around the edges of 50 the neck or mouth portion of the bottle in the well known manner. For supporting the bottle in position so that the cap thereof may be acted upon by the plunger 3, the base 1 of the frame is formed with a vertical 55 opening 4 therein and so arranged as to have its axis in alinement with the axis of the plunger 3. The neck of the bottle B is extended through said aperture from the under side of the base 1 and is held therein, 60 in the manner shown in the drawings, by suitable yielding clamping means D surrounding said neck of the bottle and providing a support which is engaged by the 65 edges of the crimped cap C.

The plunger 3 extends through a vertical bore formed in the extension 2, the latter having its upper extremity bifurcated, and an operating cam lever 12 pivoted in said bifurcation above the upper end of the plunger 3. The cam portion 12^a of the operating lever is adapted to contact with the upper extremity of the plunger 3 to cause the latter to move downwardly to perform the uncapping operation of the machine. 70 A helical spring 13 seated in a recess 14, formed in said bifurcation, is adapted to act against the projection 3^a of the plunger 3 for returning and normally holding the plunger in its raised or inoperative position, 75 as shown in full lines in Fig. 1. It will thus be seen that when the operating lever 12 is moved to a position shown in dotted lines in Fig. 1 the cam surface thereof will depress the plunger 3 against the action of 80 the spring 13 into contact with the cap or stopper C of the bottle B. Since the axis of the plunger is in line with the axis of the opening 4 in the base of the frame, the plunger will engage and depress the cap at 85 the central portion thereof, which pressure will cause the crimped edges of the cap to spread outwardly from engagement with the beaded edge 15 at the mouth of the bottle B. After the crimped edges of the 90 cap have been sufficiently spread, the operator may release the lever 12 and the spring 13 will return the plunger to its normal

95

raised position. Since the contents of these bottles are usually aerated substances, the bottles are forced downwardly out of engagement with the yielding clamping means 5 D by the action of the plunger upon said cap C. As the bottle is forced out, the cap which engages with the clamping means D surrounding the bottle mechanism is removed from the latter and left resting upon 10 the base 1 of the machine.

It is contemplated by this invention to provide means for ejecting the mutilated or removed caps from the machine after each 15 operation of the plunger 3. For carrying out this purpose any suitable means may be used that is connected to the operating lever 12 to eject the cap after the latter has been removed from the head of the bottle B. In the present instance, a preferred construction 20 is shown and comprises an ejector 16, formed of wire, or other suitable material, and bent into a substantially U-shaped formation and adapted to straddle the goose-neck extension 2 of the frame. One of the 25 arms 17 of the ejector is pivoted to the lower end of a lever 18 pivoted intermediate its ends on a pivot shaft 19. The other arm of the ejector 20 is pivoted to the lower end of the connecting arm 21, here shown as integral 30 with the pivot shaft 19, and disposed on the opposite side of the extension 2 to that of the lever 18. The closed end 16^a of the ejector is adapted to rest upon and move over the upper surface of the base 1 and to 35 act, in a sense, as a scraper or cleaner for pushing the removed caps from over the opening 4 in the base member, and finally ejecting them from the machine. Said closed end 16^a of the ejector 16 is concaved 40 or depressed inwardly to a crescent shape so as to form the ejector with a portion that will partially embrace the caps and facilitate their discharge from the machine.

The upper end of the lever 18 is connected 45 with an arm 22, rigid with the rotating pivot of the lever 12, by the connecting link 23. The arm 21 extends at such an angle that when the lever is in its ineffective position, as shown in full lines in Fig. 1, the 50 lever 18 is so actuated as to move the ejector to the limit of its ejecting movement, and when the lever 12 is moved to a position shown in dotted lines, causing the plunger 3 to actuate to remove the cap from the 55 bottle, the lever 18 will be so actuated as to draw in the ejector to a position shown in dotted lines in Fig. 1 and out of the path of the plunger 3. Now that the cap has been removed from the bottle, in the manner 60 above described, and the operator has raised the operating lever 12, which will permit the plunger 3 to return to its normal position, the ejector 16 will be moved outwardly to its position shown in full lines 65 and will engage with the removed bottle cap

and discharge the same from the machine through the opening 24 in the machine housing.

The clamping means D for holding the bottle in position so that the cap C may be 70 acted upon by the plunger 3 may be of any suitable or approved construction that will effectively hold the bottle in the base and permit the uncapping of the bottle by the action of the plunger 3. It is preferred to 75 show clamping means consisting of a plurality of arc members 5 which slidably rest in an annular mortise 6 formed in the base 1 at the upper end of the vertical opening 4. When the arc members 5 are disposed 80 in the mortise 6, the same will form a sectional ring, each section being moved toward the center by the spring 7 interposed between the sections 5 and the wall of the mortise 6. Each of the arc sections 5 have 85 their opposite ends recessed, as shown at 8, and when assembled, as clearly shown in Fig. 2, said recesses in opposing ends of adjacent sections form a slot adapted to accommodate the stop projections 9 threaded 90 in said mortise. The slots formed by the recesses 8 are sufficiently long so as to admit of a lateral sliding movement of each section, for a purpose well understood. A retaining ring 10 having a chamfered upper 95 side is designed to overlie the mortise 6 and retain the arc sections 5 in position, the ring 10 being secured to the base by fastening members 11. The concaved surface of the members 5 are also chamfered so as to provide the sectional clamping ring with an upwardly converging guide-way for facilitating the insertion of the bottle head therebetween.

It will be apparent that after the plunger 105 has spread the crimped edges of the cap B into a position shown in dotted lines in Fig. 1 and the bottle has been withdrawn from its clamped position within the opening 4, the cap C will remain upon the upper surface of the base 1, until ejected from the machine by the operation of the member 16. The operating lever 12 of the machine is herein shown and described as being operated manually. However, said lever may be 110 suitably connected with power mechanism, not shown, such as a motor, or the like, for operating the same.

The machine is adapted to be placed upon a suitable support formed with an opening 115 to permit the bottle B to be inserted in position. It is also desired to inclose the entire machine within a housing 25 which is secured to the base 1 of the frame A by any suitable fastening means. The housing is 120 formed in its upper side with an opening 26 which permits the operating lever 12 to extend and operate therethrough. The front portion of the side walls of the housing are 125 preferably arcuate to conform with the 130

curvature of the base portion, as shown in the drawings.

The foregoing clearly describes the invention; however, it is to be understood that 5 certain changes as to the construction, arrangement and combination of parts may be resorted to that fall within the legitimate scope of the appended claims.

Having fully described my invention, I 10 claim—

1. A machine of the character described, comprising, means for holding a bottle in position in said machine, means adapted to act upon the closure of said bottle for loosening said closure thereon, said holding means being arranged to remove said loosened closure from the bottle as the latter is removed from said holding means, and means coöperative with said closure loosening 15 means for ejecting said removed closure from the machine.

2. A machine for removing crimped caps from bottles, comprising, means surrounding the bottle below said cap, and adapted 20 to support the bottle in position in the machine, means for spreading the crimped edges of the cap, and a reciprocating member for ejecting said spread cap from the machine.

3. A machine for removing crimped caps from bottles, comprising, means surrounding the bottle below said cap, means for spreading the crimped edges of the cap, said first-mentioned means being adapted to remove 35 said spread cap from the bottle when the bottle is removed therefrom, and means actuated by said cap spreading means for ejecting said removed cap after the latter has been spread.

4. A machine for removing crimped caps from bottles, comprising, yielding clamping means between which said bottle is inserted and providing a support for the bottle upon which the edges of the cap rest, a reciprocating plunger for centrally depressing said cap and causing the crimped edges of the latter to be spread, and means coöperative with said plunger for ejecting said removed cap from the machine.

5. A machine for removing crimped caps from bottles, comprising, yielding clamping means between which said bottle is inserted and providing a support for the bottle upon which the edges of the cap rest, a reciprocating plunger for centrally depressing said cap and causing the crimped edges of the latter to be spread, said yielding clamping means engaging with the spread cap as the bottle is removed therefrom and retaining 55 the cap in the machine, and means coöperative with said plunger for ejecting said removed cap from the machine.

6. A machine for removing crimped caps from bottles, comprising, a yielding clamp 60 adapted to surround the neck of the bottle

below the crimped cap thereon, a plunger for centrally depressing the cap and causing the crimped edges thereof to be spread, said clamp yielding under the action of the plunger upon the cap so that the bottle is moved 70 out of clamped position, and an actuating member for ejecting said cap from the machine when the bottle is moved out of clamped position.

7. A machine for removing crimped caps 75 from bottles, comprising, a yielding clamp adapted to surround the neck of the bottle below the crimped cap thereon, a plunger for centrally depressing the cap and causing the crimped edges thereof to be spread, said 80 clamp yielding under the action of the plunger upon the cap so that the bottle is moved out of clamped position, an actuating member for ejecting said cap from the machine when the bottle is moved out of clamped position, an operating lever for the plunger, and a connection between said lever and ejecting member for actuating the latter co-operatively with said plunger.

8. A machine for removing crimped caps 90 from bottles, comprising, a yielding clamp adapted to surround the neck of the bottle below the crimped cap thereon, a plunger for centrally depressing the cap and causing the crimped edges thereof to be spread, and 95 an actuating member for ejecting said spread cap from the machine.

9. A machine for removing crimped caps 100 from bottles comprising means surrounding the bottle below said cap and adapted to support the bottle in position in the machine, means for spreading the crimped edges of the cap, and means for ejecting said removed cap from the machine after the cap has been spread.

10. A machine for removing crimped caps 105 from bottles comprising means surrounding the bottle below said cap and adapted to support the bottle in position in the machine, means for spreading the crimped edges of the cap, means for ejecting said removed cap from the machine after the cap has been spread, and a connection between said cap spreading means and ejecting means whereby the latter is actuated from the former.

11. A machine for removing caps from bottles comprising means surrounding the bottle below said cap and adapted to support the bottle in position in the machine, means for spreading the crimped edges of the cap, a reciprocating member for ejecting said spread cap from the machine, and means for actuating said cap ejecting member from the movement of said cap spreading means.

12. In a machine of the class described, the combination with a tubular expandible spreading element constituting means for receiving a bottle neck, of a yieldingly supported plunger, a cam for shifting the plunger against a cap on a bottle neck to spread 125

130

the cap upon said tubular spreading means, a lever, and a connection between the cam and lever for actuating said lever during the upward movement of the plunger to disengage the spread cap from the spreading element and the bottle neck.

5 In testimony whereof I have hereunto set

my hand in presence of two subscribing witnesses.
